to Lear Avia, Inc., Piqua, Ohio, a corporation of Illinois

Application March 28 1940, Serial No. 326,454

7 Claims. (Cl. 250—33)

This invention relates to radio directional antennae, and more particularly relates to the simplification of rotatable loop antenna structures.

It is the principal object of the present invention to provide a novel rotatable loop antenna of rugged construction with a minimum number of parts. The invention contemplates a tubular loop section rotatably supported by a depending extension in frictional bearing engagement with the base and coupled thereto by spring action. The frictional engagement in the antenna of the invention is arranged as a thrust bearing for the vertical loop section, and is also designed to be sealed against atmospheric conditions. The loop winding is constructed by threading wire through a neck portion of a continuous tubular body, and is supported in the tubular body by solidified wax which also weatherproofs the winding.

The foregoing and other objects, features and advantages of the invention will appear in the following detailed description of specific embodiments thereof, illustrated in the accompanying drawing, in which:

Fig. 1 is an elevational view of a rotatable loop antenna embodiment of the invention.

Fig. 2 is an enlarged vertical cross-sectional view taken along the line 2—2 of Fig. 1 through the support of the loop antenna.

Fig. 3 is a disassembled perspective view of the streamline supporting base of the antenna.

Fig. 4 is an enlarged cross-sectional view through a modified arrangement for the rotatable loop antenna, corresponding to a view taken along the line a—a in Fig. 2.

The assembled loop antenna embodiment of the present invention, shown in Fig. 1, comprises a continuous circular tube 10, having an extending neck portion 11 rotatably mounted on base 12 in turn secured to a mounting plate 13. The loop winding is contained within hollow tube 10, and is arranged for external connection through slip rings within base 12, to be described. Circular tube 10 is of metallic material, preferably light in weight, such as aluminum or its alloys. The top portion of tube 10 is split at 14 to minimize the effect of eddy current losses. A varnished fabric or canvas layer 15 surrounds split portion 14, to prevent entry of moisture. A collar 30 in neck portion 11 rotates on a conical bearing surface 17 secured with loop base 12. The coaction between collar 30 and bearing 17 forms an atmospherically sealed arrangement. Rotatable loop 10 is connected with shaft 18 extending through base 12. The loop 10 is rotatable with respect to fixed base 12, and is firmly

secured thereto with a locking means 20 to be described hereinafter in connection with Figs. 2 and 4.

Fig. 2 is an enlarged cross-sectional view through the loop assembly base. The metallic tube 10 is welded or brazed to extending neck portion 11 along 21. The loop winding 22 properly comprises a suitable number of turns of insulated wire, threaded through tube 10 and surrounded by solidified wax 23. Tubular loop 10 is supported on central rod 25, the top portion of which is pinned to neck 11 by off-center pin 26. Rod 25 has a central bore 27 through which the terminal leads 28, 29 of loop winding 22 extend.

An important feature of the present invention resides in the compact and structurally simplified arrangement of the loop antenna assembly. Central rod 25 bears an extending collar 30, the top surface of which is juxtaposed against neck 11, and the bottom surface of which is cupped or otherwise conically arranged to coact with conical bearing head 17. Conical head 17 extends above the surface of base 12, and is integral with a bushing 31 secured in the vertical opening in base 12. Conical head 17 of bushing 31 overlaps the openings in base 12 to prevent moisture entering therein. Bushing 31 is press-fitted in the opening of base 12, and accordingly does not rotate. It serves as a bearing for the rotatable loop 10 at rod 25 and rotatably supports collar 30 on conical head 17. Bushing 31 and its conical head 17 is preferably of a graphite or oil impregnated material, such as graphite impregnated fiber or Bakelite to constitute a suitable bearing surface.

Central supporting rod 25 of the embodiment shown in Fig. 2, is made of metal, such as aluminum or alloys thereof. The lower portion of rod 25 is of reduced diameter, and carries insulation tube 32 on which two spaced slip rings 33, 34 are supported. Slip rings 33, 34 are press-fitted on insulation tube 32, and are preferably coated with a silver layer for smooth electrical contacting with the brushes. A transverse hole is drilled through rod 25 between slip rings 33, 34, communicating with bore 27. The ends of loop leads 28, 29 are extended through central bore 27 and said transverse hole for electrical connection with associated slip rings 33, 34 as shown. Leads 28, 29 are preferably insulation covered, and their ends are soldered or brazed to edges of slip rings 33, 34.

Central supporting rod 25 extends through base 12, and beneath mounting plate 13. Suitable bushings 36 and 37 are arranged in the bot-

tom of the vertical hole through base 12, to rotatably support the bottom portion of rod 25. Rod 25 is accordingly rotatably supported at both ends of base 12. The top end of loop shaft 18 is press-fitted into an opening at the bottom of rod 25, and is secured thereto by pin 38. The loop assembly is held firmly together by locking means 20 which comprises a nut 40 on the threaded end 41 of rod 25 pressing spring washer 42 against base-plate 13, through an intermediate insulation washer 43.

An important aspect of the present invention resides in the simplified assembly of the rotatable loop 10 on its base 12 by means of a central rod 25 extending from neck 11 rotatably supported in base 12 by bushings 31 and 36, and by lock nut 40 on rod 25 pressing against a spring washer 42; permitting rotation of the loop 10 by holding conically cupped collar 30 in frictional bearing relation on conical head 17. A set screw 45 is arranged in nut 40 to lock it onto rod 25 to maintain the assembled condition of the loop intact. The conical bearing arrangement between collar 30 and head 17 seals this portion of the loop assembly from the atmosphere. As previously mentioned, the split portion 14 of the loop tube 10 is sealed from the atmosphere by fabric covering 15. Loop winding 22 is impregnated with and embedded in moisture-proof wax 23. It is thus seen that the antenna structure is well protected from the atmosphere at all possible vulnerable zones.

External electrical connection to loop winding 22 is afforded through conducting brushes 46, 47 respectively pressed against slip rings 33, 34 by springs 48, 49. The brush assembly is adjustable through screws 50, 51, and is electrically connected to the exterior by respective leads 52, 53 of loop cable 54. Loop cable 54 passes through an opening in base 12 lined by insulation bushings 55. Brushes 46, 47 and their respective components are insulated with respect to metallic base 12 through insulation linings 56, 57. The base 12 of the loop is secured to mounting plate 13 by screws 58, 59 across an insulation 45 and weatherproof layer 58.

Access to the brush assembly is readily afforded through a removable base section 60, having a contour continuous with the external surface of base 12. Base section 60 is essentially a removable cap arranged to be secured to base 12 proper through screw 61, as shown in Fig. 2. The overall contour of base 12 and section 60 is preferably streamline, as indicated in the perspective Fig. 3. Such streamline contour, when suitably aligned along the direction of travel of the vehicle, reduces the overall aerodynamic resistance of the loop assembly being particularly advantageous when used aboard aircraft. Openings 58' and 59' in base 12 indicate the ready access to the corresponding brush assemblies when cap 60 is disassembled from base 12. The graphite impregnated bushing 31 and its associated conical head 17 are fitted within the vertical opening provided in base 12.

We have found that the loop antenna assembly of the present invention withstands vigorous vibration encountered in any service condition as well as all types of weather conditions, without deleterious effects. A frictional bearing action occurs between cupped collar 30 and conical head 17, affording a suitable practical rotational support for the rotatable section 10, 11 of the loop. The assembly of loop tube 10 and rod 25 against conical bearing 17, and on base by lock nut 40 and

spring washer 42, permits ready manual rotation of the loop and presents sufficient frictional resistance against rotation to maintain the loop antenna in any angular position to which it is turned. The bearing head 17 serves as a vertical thrust bearing as well. Spring washer 42 suitably spring biases the loop assembly, facilitating the described actions and correlations. Thus, when radio directional bearings are taken on a radio transmitter by manual rotation of the loop antenna through shaft 18, the settings of the loop may be made within small angular tolerances, and the loop will hold its set positions through the frictional forces described. The graphite or oil impregnated bushing 31 and its integral conical bearing head 17 withstand long periods of service with negligible wear, and seal the interior of the loop assembly from the atmosphere.

Fig. 4 is an enlarged vertical cross-sectional view of a modified construction for the loop antenna assembly according to the present invention, and corresponds to a transverse cross-sectional view as indicated by the line a—a in Fig. 2. The principle of the modified construction of Fig. 4 is similar to that of the embodiment of Fig. 2. The difference resides in that central supporting rod 25' corresponding to rod 25 of Fig. 2 is of insulation material. Such arrangement simplifies the construction, and is preferred where the loop antenna is not subjected to substantial vibrational forces. Like numerals identify equivalent components in Fig. 4 with those of the previous figures. Central rod 25' is of a strong insulation material, such as fibrous Bakelite. Rod 25' has a metallic sleeve 62 press-fitted onto the top portion thereof. The top end of rod 25' and sleeve 62 are together press-fitted into extending neck portion 11 of loop tube 10, and secured thereto by pins 26'.

The bearing action between rotatable loop portion 10 and fixed base 12 is constituted by conical head 17 of impregnated bushing 31 coaxing with a cupped or conical portion at the end of neck 11. The thrust and frictional bearing action herein is similar to that between shoulder 30 coaxing with the conical head 17 in Fig. 2. The slip rings 33', 34' are secured within recesses in insulation rod 25' for coaction with brush assemblies corresponding to those in Fig. 2, but not seen in Fig. 4. The ends of terminal leads 28, 29 of the loop winding 22 are respectively electrically secured with slip rings 33', 34' by extending through openings drilled upon rod 25'.

A bushing 63 is set into the bottom of the vertical opening in base 12 for rotatably supporting sleeve 64 press-fitted onto the bottom end of insulation rod 25'. A pin 65 further secures rods 25' to sleeve 64. Sleeve 64 extends through base plate 13 and has a threaded end portion 41' corresponding to threads 41 at the end of rod 25. Lock-nut 40 operates on threaded portion 41 to hold the rotatable loop member in proper assembled relationship by exerting sufficient pressure against spring washer 42, for sealing and permitting proper rotatable action of the rotatable loop section on conical bearing head 17. Loop shaft 18 is inserted into the open end of sleeve 64, and is secured thereto by pin 66 indicated in dotted lines.

The rotatable loop portion containing the loop winding is assembled by threading a proper number of turns 22 in the interior of hollow tube 10, through neck 11 thereof. The split end 14 of circular tube 10 is then taped-up. Heated

liquid wax is poured into tube 10 through the open neck 11 and the sub-assembly is heated to expel entrapped air and properly impregnate the insulation on the wire 22. During this treatment, the neck portion 11 is held upwards to keep the liquid wax within the tube. On cooling, the wax 23 solidifies and serves to wax impregnate the loop winding 22 and mechanically support the winding with respect to tube 10. The tape on split end 14 is then removed, and the finished varnished fabric layer 15 is substituted. The neck 11 of the loop is attached to its central tube 25 (or 25'), which in turn is inserted in base 12 and rotatably supported therein by lock nut 40 and spring washer 42 in the manner previously described.

Although we have described and illustrated preferred embodiments of our present invention, it is to be understood that modifications may be made therein that fall within the broader spirit and scope thereof, as set forth in the following claims.

What we claim is:

1. A loop antenna comprising a rotatable section containing a loop winding and having an integral extending neck portion and a rod firmly secured to and extending from said neck portion, said rod containing a bore through which the terminals of said winding extend, a base having an opening accommodating said rod, a bushing set into said base opening having a head extending outside the base, said rotatable section having a portion directly coacting with and contacting the surface of said head to constitute a frictional thrust bearing and weather seal.

2. A loop antenna comprising a tubular section containing a loop winding and having an extending neck portion, a rod firmly secured to and extending from said neck portion and containing a bore through which the terminals of said winding extend, a base having an opening through which said rod extends, a bushing set into said base opening having a conical head extending through the top of said base, and means outside said base and secured to the external end of said rod extending through the bottom of said base for holding said tubular section in rotatable relation on said conical head.

3. A loop antenna comprising a rotatable tubular section containing a loop winding and having an extending neck portion, a rod firmly secured to and extending from said neck portion, a base having an opening accommodating said rod, a bushing set into said opening having a conical head extending to the top of said base, said rod having a collar contiguous with the end of said neck and containing a cupped conical surface directly contacting with the surface of said conical head to constitute a frictional bearing arrangement and weather seal therewith.

4. A loop antenna comprising a continuous tubular section containing a loop winding and having an extending neck portion, a rod secured to said neck portion containing a bore through which the terminals of said winding extend, a

5 10 15 20 25 30 35 40 45 50 55 60 65 70 75 80 85 90 95 100

extends, a bushing set into said base opening having a conical head extending to the top of said base, said extending neck portion having a conical cupped surface coacting with and directly contacting the surface of said conical head to constitute a frictional thrust bearing arrangement and weather seal therewith, and means secured to the extending end of said rod for holding said tubular section in rotatable relation on said base across said conical surfaces.

5. A loop antenna comprising a rotatable tubular section containing a loop winding and having an extending neck portion and a rod firmly secured to and extending from said neck portion, a base having an opening accommodating said rod, a bushing set into said opening having a conical head extending through the top of said base, means outside said base and secured to the external end of said rod extending through the bottom of said base for holding a coacting conical surface of said rotatable section frictionally against the surface of said conical head comprising a nut threaded on said rod end, a spring washer between said nut and the bottom of said base, and a member for locking said nut on said rod.

6. A loop antenna comprising a tubular section containing a loop winding and having an extending neck portion, a rod firmly secured to and extending from said neck portion, said rod containing a bore through which the terminals of said winding extend, slip rings spacedly mounted along said rod and individually connected to said winding terminals, a base enclosing said rings and a substantial portion of said rod, a frictional conical bearing arranged between said extending neck portion and the contiguous top of said base for weather-sealing the interior and rotatably supporting said tubular section, brush means mounted within said base and coacting with said slip rings, and a cap removably secured to said base and covering said brush means, said base and cap having a continuous streamline contour.

7. A loop antenna comprising a continuous tubular section containing a loop winding and having an extending neck portion, a rod secured to said neck portion and containing a bore through which the terminals of said winding extend, slip rings spacedly mounted along said rod and individually connected to said winding terminals, a base having an opening to accommodate said rod, a bushing set into said opening and having a conical head extending to the top of said base, means secured to said rod for holding said tubular section in rotatable bearing relation on said conical head comprising a nut threaded on said rod, a spring washer and a set screw for locking said nut on said rod, brushes mounted within said base individually coacting with said slip rings, and a cap removably secured to said base and covering said brushes, said base and said cap having a continuous streamline contour.

WILLIAM P. LEAR.
ARLING W. RYBERG.
